UNITED STATES PATENT OFFICE.

EDWARD T. WILLIAMS, OF SHOEMAKERSVILLE, PENNSYLVANIA.

UNDERGARMENT.

1,083,511.

Specification of Letters Patent.

Patented Jan. 6, 1914.

Application filed August 9, 1913. Serial No. 783,657.

To all whom it may concern:

Be it known that I, EDWARD T. WILLIAMS, a citizen of the United States, residing at Shoemakersville, in the county of Berks and 5 State of Pennsylvania, have invented certain new and useful Improvements in Undergarments, of which the following is a specification.

This invention relates to improvements in 10 undergarments and it is intended more particularly as an improvement in the manufacture of union suits for ladies' wear.

The object of the present invention is to 15 produce a union suit in two pieces, with a minimum of waste, as well as a minimum of labor.

The invention consists in making a garment from a tubular knitted body, such as 20 is commonly used in making garments of this character. The body or upper portion of the garment as well as one entire leg portion, is made in a single piece, and the other leg portion, which is also made in a single piece, is then attached to the body portion.

25 The invention is more fully described in the following specification and clearly illustrated in the accompanying drawing, in which:—

Figure 1 represents the front of a garment, and Fig. 2, the rear of said garment, showing my invention.

The numeral 1 designates the upper or body portion of the garment, which is of tubular knitted fabric, and it has formed 35 integral therewith, one of the leg portions, 2. This leg portion, as well as the other leg portion 3, is stitched along the inner side, where the meeting edges form the inner seam of each leg.

40 The leg portion 3 is cut from knitted fabric, and it is stitched to the upper or body portion 1, in a diagonal line from the center, at the top of the crotch opening, to a point on the waist line, indicated by the 45 numeral 4, and then across a portion of the back, as indicated in Fig. 2, by the numeral 5.

Each leg portion is formed with the usual 50 flap, 6, and this stitching across the back ends at the point where the upper edge of the leg flap terminates. It is therefore evi-

dent that the only stitching required in addition to the closing of the inner leg seams, is the single line of stitching extending from the crotch at the center of the front, to the waist line and partly across the back, which 55 will complete the garment.

The construction is extremely simple; the saving of time in manufacture and the saving of material by reducing the waste are important considerations inasmuch as very 60 slight saving in each garment of this character means an ultimate saving that may make an otherwise impracticable garment a success.

Having thus described my invention, I 65 claim:—

1. A two-piece union suit comprising a body portion having one entire leg portion integral therewith, the other leg portion comprising a single piece of fabric and attached to the body portion on a line extending from the center of the front, diagonally to the waist and then partly across the back in a horizontal line.

2. A two-piece union suit of knitted fabric 75 comprising a body portion and one leg portion formed integrally therewith, and a second leg portion attached thereto along a line extending from the crotch at the front to a point slightly beyond the vertical center at 80 the rear.

3. A two-piece undergarment comprising a tubular body portion of knitted fabric having one leg portion integral therewith, and a second leg portion formed of a single 85 piece of fabric attached to said body portion.

4. An undergarment comprising a body having one leg formed integral therewith and a separate leg portion, formed of a single piece of fabric, attached to said body portion partly across the back and from the waist line to the top of the crotch opening at the front.

In testimony whereof I affix my signature in presence of two witnesses.

EDWARD T. WILLIAMS.
